UNITED STATES PATENT OFFICE.

JAMES S. JOHNSTON, OF UTICA, NEW YORK.

MACHINE-GUN.

1,328,230.

Specification of Letters Patent. Patented Jan. 13, 1920.

Application filed March 13, 1915. Serial No. 14,226.

To all whom it may concern:

Be it known that I, JAMES S. JOHNSTON, a citizen of the United States, residing at Utica, in the county of Oneida and State of New York, have invented certain new and useful Improvements in Machine-Guns, of which the following is a specification, reference being had therein to the accompanying drawing.

10 My invention relates to a machine gun and I declare the following to be a full, clear, concise, and exact description thereof sufficient to enable any one skilled in the art to which it appertains to make and use the 15 same reference being had to the accompanying drawings in which like reference characters refer to like parts throughout the specification.

The object of the invention is to provide a 20 simple, efficient machine gun adapted for both small arms and heavy artillery use, that can be fired very rapidly without fouling or over heating. Furthermore, the gun is provided with a plurality of revolute 25 barrels and with revolute feeding drums which feed the cartridges into position to be exploded by the firing pins and thence projected through the barrels, as the same come into alinement with the cartridge receiving 30 chambers of the revolute feeding drums.

This object will be understood by referring to the drawings in which Figure 1 is a perspective view of the gun;

Fig. 2 is a side elevation of the gun, showing the same with the barrels disposed at an angle;

Fig. 3 is a fragmentary view of the gun, showing a vertical section of the forward casing or muffler;

40 Fig. 4 is a plan view of the gun, showing parts in section;

Fig. 5 is a perspective detail view of a cylindrical feeding drum somewhat enlarged;

45 Fig. 6 is an enlarged perspective detail view of a ratchet employed;

Fig. 7 is a fragmentary view of a cartridge belt, showing cartridges disposed therein;

50 Fig. 8 is an enlarged perspective view of a firing pin employed;

Fig. 9 is an enlarged side elevation of a cartridge used;

55 Fig. 10, is a detail perspective view of a crank handle employed.

Fig. 11 is an enlarged perspective view of a feeding drum, arbor and fragment of the barrels;

Fig. 12 is a perspective view of the feeding drums, showing the relative position of 60 the cartridge belts;

Fig. 13 is a vertical section of the base of the gun, showing parts connected thereto broken away.

Referring more particularly to the drawings, the barrels of the gun are represented by —1— and are rigidly attached at their outer ends to the disk 2, shouldered at 3 for the mounting of a hollow cylindrical casing or muffler 4. The opposite ends of 70 the barrels —1— are attached in a secure manner to the flange portion 5 of the feeding drum 7, so as to turn therewith. The flange 5 has the apertures 6 which are the continuation of the bores of the barrels —1— 75 and aline with the cartridge receiving chambers 22, adapted to conform to the shape of an ordinary cartridge, formed in the peripheral surface of the feeding drum 7. The flange 5 is revolvably mounted in the bearing 8 having the balls 9 disposed in the raceway 90 of the plate 10, fixed to the casing 11 by the bolts 12. The casing 11 is provided with a wall 13 having bearings for the enlarged portion 14 of the flange 5 and for 85 the outer ends of the arbors 15 and 16. The auxiliary feeding drums 17 and 18, which are equipped with the central orifices 19, are mounted upon the arbors 15 and 16 respectively in such a manner, as to turn there- 90 with. The outer peripheral surfaces of the auxiliary feeding drums 17 and 18 have formed therein the cartridge chambers 20. The chambers 20 of the auxiliary feeding drums 17 and 18 furnish the complementary 95 part to the correspondingly shaped chambers 22 of the center cylindrical feeding drum 7, which has a central orifice for mounting the same in a rigid manner upon the arbor 24, so as to turn therewith. 100

The center cylindrical feeding drum 7 and the auxiliary cylindrical feeding drums 17 and 18 are revolved in unison whereby the chambers 20 of the auxiliary feeding drums 17 and 18 and those 22 of the central feed- 105 ing drum 7 will be brought in pairs suc- cessively into complementary relation for the complete housing of the cartridges 21 by the spur gears 31, 32 and 33 keyed or otherwise fixed to the outer ends of the ar- 110

bors 15, 24 and 16, respectively. The spur gears 31, 32 and 33 are in mesh with each other in train and are actuated by a smaller spur gear 35 rigidly mounted upon a shaft 36, secured in a loose bearing in the casing 37. The smaller spur gear 35 meshes with the spur gear 32 and is driven in turn by the pinion spur gear 38 mounted to revolve with the shaft 39 of the electric motor 40. The casing 37 furnishes bearings for the inner ends of the arbors 15, 16 and 24. There are mounted upon the arbors 15 and 16, the ratchets 41 and 42, respectively, which turn with the said arbors and when assembled lie partially within the recesses 43 formed in the ends of the auxiliary cylindrical feeding drums 17 and 18, so that the teeth 44 project a little beyond the recesses and outer edge of the said feeding drums 17 and 18. The teeth 44 of the ratchets 41 and 42 are engaged by the detents 45, depending from the ends 46 of the firing pins 47, urged normally toward the cartridge receiving chambers 20 and 22, as the same come into complementary relation, by the coiled spring 50 bearing at one end against the heads 46 of the firing pins 47 and at the other against the walls of the casing 37. The points 48 of the firing pins 47 will strike, when permitted to do so by the dropping of the detents 45 behind the elevations of the teeth 44 of the ratchets 41 and 42, the primers 49 of the cartridges 21 to explode the same.

The inner bores of the barrels —1— are provided with spiral grooves or turns, whereby to cause the projected bullets to revolve in their flight, as is well known in the art.

The arbor 24 is provided with a central cylindrical recess, which is continuous through the feeding drum 7 and flange 5, and adapted for the reception of a long bar or shaft 60 having a loose bearing in said arbor 24 at one end and in the disk 3 at the other. The end of the shaft 60 adjacent the muzzle of the gun supports a fan 61, which is disposed within the casing or muffler 4 and clears the range of the barrels —1—. The fan 61 is revolved, whereby to draw the hot air from the barrels —1— and the feeding drums 7, 17 and 18 for cooling purposes by the motor 40, connected to the shaft 60 by a belt 62 running over the grooved pulleys 63 and 64 keyed or fixed to the shafts 39 and 60 respectively. The feeding drums 7, 17 and 18 are, furthermore, provided with the holes 64, whereby to aid in cooling the same.

The casing 11 has the openings 81 suitably disposed for the admission and exit of the cartridge receiving belts 66 and is detachably held to the casing 37, which is shoudered at 76 for the reception of the adjacent edge of the casing 11, by the bolts 12.

The casing 37 is provided with the trunnions 50, having loose bearings in the upper ends of the standards 51, secured at their lower portions by bolts or other suitable means to the dial 52, mounted upon the base 70 53 having a shoulder 54 and raceways 55 and 56 for the balls 57. This mounting of the gun permits the same to be moved to any degree in a horizontal or perpendicular plane, whereby the muzzle may be directed 75 toward an object in any position with reference to the gun. A handle 58 is mounted to the side of the gun for holding the muzzle of the same in any given direction.

The operation of the firearm is effected 80 by first loading the cartridges 21 into the metallic belts 66 which are provided with the slits 67, 68 and 69 for the purpose. The rear edges of the belts 66 are turned down slightly at 91, whereby to engage the grooves 85 70 formed in the cartridges 21 adjacent the primers 49 thereof, so as to prevent said cartridges from being jarred loose from the belts 66. One of the belts 66 is then fed upward from below between the feeding 90 drums 18 and 7 and the other from above downward between the feeding drums 17 and 7. The gun is positioned for shooting. The front sight 100 and the rear sight 101 being used to secure the proper range. The 95 motor 40 is started, or if a manual operation is preferred, the pinion 38 can be pushed clear of the spur gear 35, which may be revolved by a crank 75 having a socket for detachably engaging the squared end 92 of 100 the shaft 36, whereby to revolve the spur gear 35 and, therefore, the gears 31, 32 and 33. The revolution of the gears 31, 32 and 33 will cause the feeding drums 7, 17 and 18 to turn and thereby automatically draw the 105 cartridge belts 66 and the cartridges 21 therein along to the firing position, which occurs as the chambers 22 of the center feeding drum 7 and the corresponding chambers 20 of the auxiliary feeding drums 17 and 110 18 come into complementary relation opposite or in prolongation of the corresponding bores of the barrels —1—. At this point in the revolution of the feeding drums 7, 17 and 18, the primers of the two cartridges 21 115 will be struck simultaneously by the heads 46 of the two firing pins 47, which are urged forward normally by the coiled springs 50, as the detents 45 drop into the depressions 80 of the ratchets 41. Hence the bullets 120 from the cartridges 21 will be discharged through two of the barrels —1—, located diametrically opposite each other, synchronously, while the other six barrels —1— are allowed to cool. As the barrels —1—, feeding drums 7, 17 and 18, revolve continuously, the bullets will be projected through the said barrels —1— in pairs successively. The base 53 is adapted for mounting upon any suitable foundation, if desired to use 130

the invention as a stationary gun, however, it can be attached to the chassis of an automobile for use in military field service.

Having thus described my invention, what I claim as new and desire to secure by Letters Patent is:

1. In a machine gun, barrels for the projection of bullets, cylindrical feeding drums having chambers for the reception of cartridges, holes in said drums for cooling purposes, gears for revolving said barrels and feeding drums, firing pins actuated by ratchets and springs for discharging said cartridges, whereby the bullets thereof will be projected through certain of said barrels simultaneously, mechanical means for cooling said gun, and a revolute dial for mounting the same.
2. In a machine gun, a plurality of barrels adapted for the projection of bullets, cylindrical feeding drums having chambers for the reception of cartridges, arbors for mounting said feeding drums, gears attached to revolve with said arbors, means for actuating said gears, whereby to bring the cartridges into firing position, firing pins for exploding said cartridges, ratchets and springs for actuating said firing pins, a shaft disposed in a recess within one of said arbors, a fan attached to the end of said shaft, and an electric motor for revolving said shaft and fan to cool the gun.

In testimony whereof I have affixed my signature in the presence of two witnesses.

JAMES S. JOHNSTON.
